UNITED STATES PATENT OFFICE.

EMIL A. HOEFER, OF FREEPORT, ILLINOIS, ASSIGNOR TO GEORGE W. WARNER, OF SAME PLACE.

DESIGN FOR A HAND-TRUCK.

SPECIFICATION forming part of Design No. 26,570, dated January 26, 1897.

Application filed May 29, 1896. Serial No. 593,669. Term of patent 7 years.

To all whom it may concern:

Be it known that I, EMIL A. HOEFER, a citizen of the United States, residing in the city of Freeport, county of Stephenson, and State 5 of Illinois, have invented and produced a new and useful Design for Hand-Trucks, of which the following is a specification, reference being had to the accompanying drawing, forming a part hereof.

○ Said drawing represents a perspective view of a hand-truck embodying my novel design.

A hand-truck embodying my novel design embraces a longitudinal frame consisting of two external longitudinal side pieces lying 5 parallel with each other, formed by flanged metal bars or angle-irons of L shape in cross-section, which are arranged with the free edges of the flanges directed inwardly and downwardly and with the said flanges in horizontal and vertical planes, so that the outer and upper surfaces of each bar presents a flat or plane surface. Said bars are connected with each other by metal cross-pieces

extending beneath the upper or horizontal flanges and secured to the depending or vertical flanges of the bar. The side pieces are curved upwardly in uniform curved lines at the forward end thereof to constitute a handle for the truck, and preferably one or two of the cross-pieces connecting said bars will be 25 located near the upper end of said curved portion to afford a convenient means of grasping the truck.

I claim--

The design for a hand-truck substantially 35 as shown and described.

In testimony that I claim the foregoing as my design I affix hereto my signature, in the presence of two subscribing witnesses, at Freeport, Illinois, this the 23d day of May, 40 1896.

EMIL A. HOEFER.
